SEWING MACHINE ATTACHMENT FOR CIRCULAR DECORATING

Gordon Florian, Fairfield, Conn., assignor to The Greist
Manufacturing Company, New Haven, Conn., a cor-
poration of Connecticut

Application January 13, 1958, Serial No. 49,244

Term of patent 7 years

(Cl. D70—2)

Fig. 1 is a top plan view of a sewing machine attachment for circular decorating embodying my new design; and

Fig. 2 is a side elevational view thereof.

I claim:

The ornamental design for a sewing machine attach-
ment for circular decorating, substantially as shown.
